UNITED STATES PATENT OFFICE.

FRANK M. DILLIE, OF CINCINNATI, OHIO.

DESIGN FOR COVERS FOR BIBLES.

Specification forming part of Design No. 10,943, dated December 3, 1878; application filed November 19, 1878.
[Term of patent 7 years.]

To all whom it may concern:

Be it known that I, FRANK M. DILLIE, of Cincinnati, in the county of Hamilton and State of Ohio, have originated and designed a Cover or Lid for Bibles, which is fully set forth in the following specification and accompanying photographic illustration, making part of this specification.

My design is based on the ornamentation and outline formed by a Maltese cross, A.

Raised panels having beveled edges are formed around this cross, B, having stamped thereon a representation of Solomon's Temple, the hour-glass, and the altar. This forms the panel for the upper limb of the cross, and E E, having a beveled groove, F, separating them, form the panels for the lower limb of the cross. The panels C C D D are similar to each other in form, V-shaped, and disposed around the side limbs of the cross.

It will be noticed that this disposition of the grooves between the panels forms seven panels, which is regarded as a sacred number.

The words "Holy Bible" are impressed on the upper and lower limbs of the cross, as shown; also the representation of a cross and crown, and a small star in the center.

On the different panels are representations of Bible suggestions—namely, Hope, Faith, Jacob's Ladder, the Ark, and emblem of Peace, the Hive, Industry, and the All-seeing Eye—although I do not lay any claim to the use of these representations or to their arrangement, others being equally as appropriate.

What I claim as my invention is—

A design for a Bible-lid, in which the central figure is a Maltese cross, surrounded by seven raised bevel-edged panels, disposed as above shown, and suitably stamped and ornamented, substantially in the manner herein described.

FRANK M. DILLIE.
